UNITED STATES PATENT OFFICE

131,825

DESIGN FOR A DISH

Bennett Russell, Yakima, Wash.

Application August 13, 1941, Serial No. 102,823

Term of patent 14 years

To all whom it may concern:

Be it known that I, Bennett Russell, a citizen of the United States of America, residing at Yakima, county of Yakima, and State of Washington, have invented a new, original, and ornamental Design for a Dish, of which the following is a specification, reference being had to the accompanying drawing, forming a part thereof, wherein:

I claim:

The ornamental design for a dish, as shown.

BENNETT RUSSELL.
